APPARATUS FOR PILING RUGS

Lee A. Jackson, Needham, Mass.

Application May 9, 1934, Serial No. 724,729

16 Claims. (CL 112—9)

In the piling of rugs, carpets or the like, there has developed a type of hand made article usually known as "hooked". Such rugs comprise a fabric foundation as of canvas or burlap through which the piling is drawn as loops. The loops are then cut to free the ends and give a level nap surface.

This so-called hooking has usually been done on a plain frame or stretcher in which the foundation could be held smooth and tight. Hooks of various types were pushed through to draw up the loops and develop the pattern of the pile. The method was slow and laborious. Due to the free hand basis of operation there was a wide variety 10 in result and in the amount of material used or unused.

As the piling is usually made of carpet yarns, there is considerable cost involved in rug making. Furthermore, as these rugs are usually of varied 20 pattern and color the matter of selecting or matching yarn has caused much difficulty and waste. If more than enough yarn of the kinds or colors is bought there is the obvious waste of the residue. If too little be bought, by the time the 25 shortage is discovered there is apt to be difficulty in matching any color needed to fill out the pattern. Colors in stock vary in dyeing from time to time.

My invention contemplates an improvement in 30 the method and provides for simple procedure for the method for experienced or inexperienced and also for apparatus to make such methods feasible and easy.

The improvement in the product and the savings in time and labor will appear more fully from 35 the following description, reference being made to the accompanying drawing. In the drawing I have shown a simple illustrative basis for my invention as follows:

40 Fig. 1 is a front elevation of a simple device as used in accordance with my invention.

Fig. 2 is a side view of the same.

Fig. 3 is an enlarged section through the temple bars showing one strip of piling looped but not 45 cut.

Fig. 4 is a similar section showing the work progressed for the development of another strip of piling.

50 Fig. 5 is an illustrated detail showing the manner in which the loops are cut.

Fig. 6 is an illustrative view showing how different depths of loop bars may be substituted to produce different depths of piling and

55 Fig. 7 indicates a variant form of loop bar in

which the base is solid and the upper member channelled.

In the device as illustrated in the drawing I may provide a pair of side rails 1. Each has a split bearing 2 adjacent one end clamped by a 5 wing nut 3. In these bearings is journaled a beam 4. The beam 4 is what may be termed the rug beam. At their opposite ends the rails 1 are connected by a rigid cross piece 20. Adjacent this cross piece 20 is rotatably mounted on the 10 rails 1 a second beam 5 which holds the foundation material F which is carried over and wound on the beam 4.

These simple members constitute in the form shown a light, oblong, open framework easily 15 handled or positioned as the worker may wish. Pivotally clamped as at 6 on the beam 5 is a pair of arms 7 connected by a cross bar 8.

The edges of the arms 7 are recessed to form longitudinal pockets 9 covered by latches 10 pivoted to the arms 7 at 11. In these pockets 9 I set plates 12 provided with notches 12¹ for holding the ends of a series of parallel cross bars 13 U-shaped in cross section. These bars may be of any depth according to the length of loop or 25 depth of the pile desired.

The arms 7 are adjusted or positioned at an angle to the side rails 1 by hook-like braces 14.

This adjustable frame member therefore constitutes what might be called by analogy a temple element. When the main frame is supported across a chair or table with the temple end towards the worker it forms an elevated guide for the foundation F which is tensioned up on one of the beams.

In practicing my method with such equipment, the procedure is generally as follows: The foundation F is usually stencilled with a pattern which according to my invention is on the side next to the worker and thus in plain sight as the work 40 progresses.

The pile is also developed on this side of the foundation fabric. In most former practices the pile was developed on the side opposite from the pattern and thus was inconveniently and inefficiently disposed. Such practices coupled with the irregular and unsystematic progression of the pattern made for more waste of time and material.

By my system I impose an absolute order and 50 at the same time a simple procedure based on the indicated arrangement of parallel rows. These are definite and accurate and the computation of the required yarns necessary for the nap or fill can be assured.

55

My system departs from the common practice in that it employs a simple needle N as compared with the usual hook. My bars 13 provide for a normal lateral development of the pattern in rows. By my method I am able to provide for immediate reasonable results even for the inexperienced in the wholesome adventure of such an art. The advantage of having the result visible on the pattern side of the foundation 10 is obvious.

My invention permits of an overcast system. It potentially differentiates overcasting from hooking, although common hooking may be practiced on such frames as I have indicated 15 herein.

In practice the foundation F is given a partial turn (outside of the pattern on the rug beam 4). The other end of the foundation is rolled on the beam 5. In practice this leaves a slack in 20 the interior of the frame.

The temple frame is then set up at an angle to the main frame members 1. The beams are adjusted to give the desired tension to the foundation F which is then ready to receive the pile. 25

According to my method of procedure I fill the bars 13 with a series of tensioned overcast loops of yarn Y . In this the work may proceed from right to left or left to right according to the manual habit of the worker. As the work develops from bar to bar a succession of these lateral overcast, tensioned loop rows appear until 30 a section or panel is formed.

Each succeeding row tends to lock the preceding row of loops. As shown the frame or panel 35 of bars 13 is twelve in number (for example), as shown in Fig. 3. These are filled and the first ten bars of the frame or set are slit (as shown in Fig. 5), to cut or free the tensioned loops. For this purpose an ordinary safety razor blade R 40 may be run through the channel of the U-bars 13 . This leaves two (or more as desired) rows of loops in place to act as guides in the pattern and as stops to the succeeding rows. The free bars 13 may now be removed, the retained bars 45 13 unhooked and the foundation F advanced. In this the rug beam clamp screw 3 is merely slackened and the beam rotated to the required accommodation of foundation takeup and tension. In this movement such bars as were left locked 50 in the closed pile are moved with the foundation. In this there is an exchange or progression of bars 13 , as indicated in Fig. 4.

The work does not have to proceed as a continuous progression. As desired the worker may 55 advance on the design and loop in another section. This is a mere matter of shifting the foundation F to position the work at the zone of fabrication.

I have indicated in Fig. 6 by a simple comparative diagram how three (or more) different widths of loop bars may be used interchangeably in the same frame.

We may consider the bar 13 as of maximum width to fill the slot 12^1 but it will be seen that 65 a bar of lesser width or depth 13^1 may be substituted in cases where a short pile is desired. In such a substitution I provide a filler block or strip 13^2 to go beneath the latch 10 to fill the space left between the top edges of the bars 13 70 and the latch 10 .

In the same bracketed figure 13^2 indicates a still narrower loop bar for making a still shorter pile. Its corresponding filler block or strip 13^3 is intended to be shown as filling the resulting 75 vacancy and backing up the latch 10 .

In Fig. 7, I have shown a modification of the loop bar comprising a very shallow channel 13^3 backed up by a solid bar 30 . Only a shallow groove or opening or slit is needed for the loop cutting blade. These members may be separate 5 and interchangeable as before indicated in which case I usually keep the channel 13^3 constant and vary the depth of the backing bar 30 to get the desired total depth.

In Fig. 2 no effort is made to indicate the contact of the latch 10 with the loop bars 13 . This figure is intended to indicate general assembly only in the simple type of frame used herein for illustrative purposes. The very simplicity of the frame shown is of advantage as it is made of 15 wooden strips and is light and inexpensive and well adapted to the use of the craft.

Obviously sheet metal or other material could be substituted to make more elaborate frames.

As the indicated device is intended primarily 20 for home or craft work, it is only necessary to understand that the piling is to be done by hand.

If we may assure the foregoing suggestion of procedure, the rug or like work or product will be developed as above described. 25

The exact mechanism of the frame while inconsequential to the larger concept is really of immediate practical service. In practice its efficiency is demonstrated.

The structure may be varied and the mechanisms will necessarily be modified to meet personal habits, ideas or tastes. 30

What I therefore claim and desire to secure by Letters Patent is:—

1. In a rug piling frame, a pair of side rails, 35 a pair of beams journaled at opposite ends thereof for holding a foundation web, means for clamping the beams, a temple frame hinged to the side rails and having a longitudinal recess, a series of transverse loop bars, a bracket plate 40 in said recess, said plate having receiving slots for the bar ends for detachably supporting the bars across the foundation.

2. In a rug piling frame, a pair of side rails, 45 a pair of beams journaled at opposite ends thereof for holding a foundation web, means for clamping the beams, a temple frame hinged to the side rails and having a longitudinal recess, a series of transverse removable and interchangeable loop bars, a bracket plate in said recess, said 50 plate having receiving slots for the bar ends for detachably supporting the bars across the foundation.

3. In a rug piling frame, a pair of side rails, 55 a pair of beams journaled at opposite ends thereof for holding a foundation web, means for clamping the beams, a temple frame hinged to the side rails and having a longitudinal recess, a series of transverse loop bars, a bracket plate in each 60 recess, said plate having receiving slots for the bar ends for detachably supporting the bars across the foundation, and means for angularly supporting the temple frame.

4. In a rug piling frame, a pair of side rails, 65 a pair of beams journaled at opposite ends thereof for holding a foundation web, means for clamping the beams, a temple frame hinged to the side rails and having a longitudinal recess, a series of transverse removable and interchangeable loop bars, a bracket plate in each recess, said 70 plate having receiving slots for the bar ends for detachably supporting the bars across the foundation, and means for angularly supporting the temple frame.

5. A rug piling frame comprising side rails, a 75

- pair of beams journaled at opposite ends thereof for holding a foundation web, means for clamping the beams, a temple frame movably supported relative to the side rails, plural transverse loop bars, and means for detachably supporting the bars across the foundation. 5
6. In a rug piling frame, a frame, a draft beam at opposite ends of said frame for a web foundation, means for clamping the beams in the frame, a temple frame movable relatively to said frame, a series of transverse loop bars, means for detachably supporting the bars across the foundation, and means for angularly adjusting the temple frame. 10
7. In a rug piling frame, a frame, a draft beam at opposite ends of said frame for a web foundation, means for clamping the beams, a temple frame movable relative to the sides of the frame and having a longitudinal recess, a series of transverse loop bars, a bracket plate in each recess and having receiving slots for the bar ends for detachably supporting the bars across the foundation, and means for angularly adjusting the temple frame. 15
8. In a rug piling frame, opposite supports for holding a rug foundation, a series of independently removable transverse parallel U-shaped loop bars, and bar receivers in the frame detachably and interchangeably supporting said bars across the foundation. 20
9. In a rug piling frame, opposite means for movably holding a rug foundation, a series of independently removable transverse parallel loop bars, and means for detachably and interchangeably supporting said bars across the foundation course. 25
10. Rug piling apparatus comprising side rails, rug foundation supports journaled in said rails and a work temple hinged to said rails and adapted to be adjustably disposed over said rug foundation, said temple including a plurality of loop bars and means for detachably supporting the same across the rug foundation. 30
11. Rug piling apparatus comprising side rails, rug foundation supports journaled in said rails and a work temple hinged to said rails and adapted to be adjustably disposed over said rug foundation, said temple comprising a pair of longitudinally recessed arms one pivoted to the forward end of each of said rails, a slotted bracket in each of said temple arm recesses and a loop bar detachably supported by its ends in said slots across the rug foundation. 35
12. Rug piling apparatus comprising side rails, rug foundation beams journaled in said rails and a work temple hinged to said rails and including a pair of arms, a bar connecting the same and over which said rug foundation passes, and work guides supported by said arms and extending transversely over said rug foundation. 5
13. Rug piling apparatus comprising side rails, rug foundations beams journaled in said rails and a work temple hinged to said rails and comprising a pair of arms one pivoted to the forward end of each rail, a bar connecting said arms and over which said rug foundation passes, and a work guide removably mounted in said arms and extending transversely over said rug 10 foundation, and means for vertically adjusting said arms and thereby positioning said, foundation in desired work position. 15
14. Rug piling apparatus comprising side rails, rug foundation beams journaled in said rails and a work temple hinged to said rails, means for elevating said foundation to desired inclined work position including a rug foundation support and means for raising and lowering said foundation support, and a work guide extending transversely over said rug foundation and supported by said foundation raising and lowering means. 20
15. Rug piling apparatus comprising a rug foundation supporting frame including side rails and front and rear rug supporting beams journaled in said rails, and a work temple including a pair of spaced arms secured to said front rug beam, a cross bar connecting said arms and over which the rug foundation passes, longitudinal pockets in said arms, notched plates in said 30 pockets and a work guide extending transversely over said rug foundation and supported in said notches, and means locking said guide in said notches during its period of use. 35
16. Rug piling apparatus comprising a rug foundation supporting frame including side rails and front and rear rug supporting beams journaled in said rails, and a work temple including a pair of spaced arms secured to said front rug beam, a cross bar connecting said arms and 40 over which the rug foundation passes, and means for guiding the work and for determining the depth of the pile to be produced, including a plurality of interchangeable cross bars of varying depths, each adapted to extend over said rug foundation while in use, and means for holding said bars in work position. 45
